GARMENT HANGER

James D. Coney, Chicago, Ill.

Application October 9, 1943, Serial No. 505,623

4 Claims. (Cl. 223—88)

This invention relates to garment hangers and more particularly to the combination wire frame and paper tube strut type, although certain features thereof may be employed with equal advantage in connection with other types of garment hangers or for other purposes.

It contemplates more especially an improved garment hanger that embodies a combination wire frame and paper tube strut which can be readily assembled by the user to provide an improved hanger construction that is capable of sustaining heavy garments without the usual tendency of the wire hanger portion becoming separated from the paper tube strut.

One object of the present invention is to simplify and improve the construction of garment hangers embodying a combination wire frame and paper tube strut.

Another object is to provide an open wire garment frame for ready attachment to a paper tube strut without placing either element under tension, deformation or strain.

Still another object is to provide a garment hanger of the type mentioned having wire arms terminating in specially shaped extremities to provide ready engagement with a paper tube strut without requiring either of the elements to be under tension, deformation or other strain in effecting the assembly thereof.

A further object is to provide an improved garment hanger constructed partially from non-metallic material to afford complete garment hanger utility.

A still further object is to provide a garment hanger of the type mentioned having wire arms terminating in enclosed loops to provide ready engagement with a paper tube strut without requiring either of the elements to be under tension, deformation or other strain in retaining the assembly thereof.

Still a further object is to provide a garment hanger of the type mentioned having wire arms terminating in looped extremities complementary to engaging notches in the paper tube strut to enable their assembly without placing either element under tension, deformation or other strain.

Other objects and advantages will appear from the following description of an illustrated embodiment of the present invention.

In the drawing:

Figure 1 is a front view in elevation of a garment hanger embodying features of the present invention.

Figure 2 is an enlarged end view in elevation of the garment hanger shown in Figure 1.

Figure 3 is a fragmentary sectional view in elevation of an end portion of the wire arm together with the complementary portion of the paper tube strut showing the assembled construction and relation of the garment hanger elements.

Figure 4 is a fragmentary sectional view in elevation of an end portion of the wire arm showing the looped extremities of the wire frame portion.

Figure 5 is a fragmentary front view in elevation of an end portion of the assembled wire frame and paper tube strut assembled to receive a fastener to illustrate the manner of supporting a skirt or other garment therewith.

Figure 6 is a fragmentary sectional view in elevation taken substantially along line VI—VI of Figure 5.

Figure 7 is a fragmentary perspective view of one end of the paper strut showing the complementary features enabling assembly with the wire frame portion.

The structure selected for illustration is not intended to serve as a limitation upon the scope or teachings of the invention, but is merely illustrative thereof. There may be considerable variations and adaptations of all or part of the teachings depending upon the dictates of commercial practice.

The present embodiment comprises a wire or frame 10 of light gauge wire construction providing a double strand twisted shank 11 which terminates in a hook 12 of standard or suitable shape and construction. The shank 11 extends downwardly in garment supporting arms 13 and 14 that diverge to provide the final angular configuration conforming to the suitable support of a garment such as a coat.

The diverging arms 13—14 of the frame 10 extend outwardly to merge in rounded ends 15 and 16 that are inwardly curved to present downwardly inclined and converging extensions 17. Each of the inwardly converging extensions 17 terminate in downwardly extending enclosed loops 18 and 19 comprising a part of the frame arms 13—14, respectively.

The downwardly extending frame loops 18—19 have their terminal ends 20 extending upwardly and outwardly at an inclined angle to present opposing engaging edges 21 and 22 substantially in horizontal alignment to frictionally fit into horizontal slots 23 provided in the bottom of a paper tube strut 24.

The paper tube strut 24 is preferably though not essentially convoluted from jute or other suitable materials to provide rigid tubular cylindrical bar supported between the curved ends 15-16 of the frame 10 as will appear more fully hereinafter.

The length of the paper tube strut 24 is somewhat greater than the distance between the curved frame ends 15-16, since slots 25 are provided in the top portion of the paper tube strut 24 to communicate with both open ends 26 and 27 thereof to permit free registry with the curved ends 15-16 of the wire frame 10. This precludes the rotation of the paper tube strut 24 relative to the frame arms 13-14 and provides for the insertion of the downward converging frame arm extensions 17 so that the looped extremities 18-19 thereon will enter and protrude through the bottom slots 23 that are spaced from the ends 26-27 of the tube a distance corresponding with the spacing of the wire frame loops 18-19.

The looped frame extremities 18-19 are shaped and sized so that contact with the tube slots 23 is effected along a horizontal line to establish contact therewith as at 21-22, thereby preventing lateral movement of the wire arms 13-14 in either direction and maintaining the initial shape and diverging angularity thereof irrespective of the garment load thereon.

It should be observed that this arrangement and method of assembly involves no tension, deformation or strain on either the wire frame 10, its arms 13-14, or its ends 15-16 or on the paper tube strut 24 as these elements are initially shaped, stamped and constructed to be perfectly complementary to each other so that they can be shipped knocked-down to save transportation space and thereafter readily assembled by the user without entailing any appreciable time, effort or inconvenience.

Any stresses or strains imparted to the garment frame 10 by virtue of the garment load will not affect the assembled relation of the garment supporting elements. The assembled relation of the component elements is maintained owing to the fact that the inwardly curved frame arm ends 15-16 register with the paper tube strut slots 25 to prevent relative turning therebetween. Any tendency for inward or outward displacement of the frame arms 13-14 relative to the tubular strut 24 is precluded by the looped extremities 18-19 which protrude in and through the bottom slots 23 of the strut 24 so that there is a horizontal line of contact between the extremities of the slot 23 and the extreme edges 21-22 of the looped extremities 18-19. This effects a dependable interengagement between the frame ends 15-16, on one hand, and the looped frame extremities 18-19, on the other hand, with the slots 25-23, respectively, in the tubular strut 24, thereby retaining the wire frame 10 and the tubular paper strut 24 in assembled relation without tension, deformation or strain on either or both other than the garment load thereon.

In order to support garments such as women's skirts from the frame 10 without doubling such garments over the tubular strut 24, any suitable fastener such as safety pins 28 extend through the loops 18-19 for engagement with the waistband of the skirt or other garment to effect the suspended support thereof. With these fasteners, such garments as skirts can be supported without folding or other undesirable creasing. This

also permits the paper tubular strut 24 to be inserted between the frame ends 15-16 and their downwardly inclined and converging extension 17 so that the enclosed looped extremities 18-19

5 can be lodged in the bottom tube slots 23 to effect interengagement against accidental separation, because the wire frames 10 and the tubes 24 can be packed more advantageously and efficiently when separated from each other. These component elements 10-24 are furnished for assembly by the purchaser who also can supply the suspended garment fasteners 28 as independent accessories within the dictates of commercial practice.

15 The fact that the component hanger elements 10-24 are initially sized to be interfitting without any requirement to effect their assembled retention by tensioning, deforming or straining any portion thereof, the purchaser can perfectly 20 assemble these without any particular equipment or previous experience or utilization of force which would permanently impair the paper tube 24.

While I have illustrated and described a preferred embodiment of this invention, it must be understood that the invention is capable of considerable variation and modification without departing from the spirit of the invention. I, therefore, do not wish to be limited to the precise 30 details of construction set forth, but desire to avail myself of such variations and modifications as come within the scope of the appended claims.

I claim:

1. In a garment hanger, a supporting hook 35 and a frame of wire having downwardly diverging arms, inwardly curved arm ends on said frame, curved terminals on said arm ends defining strut connecting members, and an open end tubular strut having complementary connecting means therein proximate to the open ends thereof, said inwardly curved arm ends extending for their normal spread axially through the open ends of said tubular strut with said curved terminals fitted into said complementary connecting means from within said tubular strut to preclude their separation when said frame ends extend for their normal spread through the open ends of said tubular strut.

2. In a garment hanger, a supporting hook and a frame of wire having downwardly diverging arms, inwardly curved arms ends on said frame, curved loop terminals on said arm ends defining tube connecting members, and an open end tubular strut having complementary connecting means 45 therein proximate to the open ends thereof, said inwardly curved arm ends extending for their normal spread axially through the open ends of said tubular strut with said curved loop terminals fitted into said complementary connecting means from within said tubular strut to project there-through as hanger loops and preclude separation between said frame and strut when said frame ends extend for their normal spread through the open ends of said tubular strut.

3. In a garment hanger, a supporting hook and a frame of wire having downwardly diverging arms, inwardly curved arm ends on said frame, curved loop terminals on said arm ends defining tube connecting members, and an open end tubular strut having complementary slots therein 50 proximate to the open ends thereof, said inwardly curved arm ends extending for their normal spread axially through the open ends of said tubular strut with said curved loop terminals fitted into said complementary slots from within

said tubular strut to project therethrough as hanger loops and preclude separation between said frame and strut when said frame ends extend for their normal spread through the open ends of said tubular strut.

4. In a garment hanger, a supporting hook and a frame of wire having downwardly diverging arms, inwardly curved arm ends on said frame, enclosed curved loop terminals on said arm ends defining tube connecting members, and an open end tubular strut having complementary slots therein proximate to the open ends thereof, said tubular strut having end communicating notches therein to reduce the length of the tubular strut

therebetween to correspond with the normal spacing of said inwardly curved arm ends that register therewith, said inwardly curved arm ends extending for their normal spread axially through the open ends of said tubular strut with said enclosed curved loop terminals fitted into said complementary slots from within said tubular strut to project therethrough as hanger loops and preclude separation between said frame and strut when said frame ends extend for their normal spread through the open ends of said tubular strut.

JAMES D. CONEY.
